(57) **CLAIM**

The ornamental design for a bottle, as shown and described.

DESCRIPTION

FIG. 1 is a front perspective view of a bottle showing my new design;

FIG. 2 is a front elevation view of the bottle shown in FIG. 1;

FIG. 3 is a rear elevation view of the bottle shown in FIG. 1;

FIG. 4 is a right side view of the bottle shown in FIG. 1;

FIG. 5 is left side view of the bottle shown in FIG. 1;

FIG. 6 is a top view of the bottle shown in FIG. 1;

FIG. 7 is a bottom view of the bottle shown in FIG. 1;

FIG. 8 is another front perspective view of the bottle of FIG. 1; and,

FIG. 9 is a cross-sectional view of the bottle of FIG. 1; taken along line 9-9 in FIG. 6.

The broken lines in the drawings depict portions of the bottle that form no part of the claimed design.

1 Claim, 9 Drawing Sheets
